CRACKING OF OIL

Eugene C. Herthel, Chicago, Ill., assignor to Sinclair Refining Company, Chicago, Ill., a corporation of Maine

Application September 24, 1923, Serial No. 664,502

2 Claims. (Cl. 196—48)

This invention relates to an improved method and apparatus for cracking heavier hydrocarbon oils for the production of lighter hydrocarbon oils therefrom.

- 5 In the cracking of heavier hydrocarbon oils in externally heated stills, the heavier oil is heated to a high temperature under pressure and the heat necessary for raising the oil to the cracking temperature is applied directly to the walls of the 10 pressure still, in the case of a shell still, and to the heating tubes in the case of a tube still. As the cracking operation progresses, the formation of carbon and tar constituents takes place and the extent to which the cracking operation 15 can be carried in a single run is limited by the accumulation of such constituents which tend to settle or separate out on the heating surfaces and to form a layer of so-called carbon thereon which interferes with the heat transfer and, unless periodically removed by cleaning, causes 20 overheating of the walls or tubes of the still. To avoid or minimize the danger of such carbon separation on the heating surfaces, the run is commonly stopped before the accumulation of heavy 25 tar constituents becomes too great, or the tar is continuously withdrawn and fresh feed supplied to maintain the charge in a sufficiently fluid condition to permit continued operation for a longer period of time. The danger of such carbon separation and resulting failure of the still walls or 30 tubes is greatest where the intense heat of the furnace gases first comes in contact with the still walls or tubes and where the greatest amount of heating takes place.
- 35 In carrying out the present invention, the pressure still itself, whether of a shell or tube type, advantageously is protected from the intense furnace heat, and this heat is applied in such a way as to increase the efficiency and capacity of 40 the still.

In carrying out the present invention, I find it advantageous to provide an auxiliary heating coil arranged between the firebox and the main heating surfaces of the still so that the auxiliary 45 coil will be subjected to the hottest heating gases and the intense furnace heat thus utilized and reduced before the heating gases pass over the heating surfaces of the still proper. By arranging a preliminary cracking coil intermediate the firebox and the still proper I utilize the highest temperature of the heating gases to heat the oil flowing through the auxiliary coil and I then use the furnace gases at a lower temperature for heating the main charge of oil in the still itself.

55 The auxiliary cracking coil is used for carrying

out a separate cracking operation which may be independent of the cracking operation carried out in the pressure still itself; but which is advantageously combined with the pressure still so that the oil subjected to the cracking operation in the preliminary cracking coil is discharged into the main body of oil in the pressure still.

Where the preliminary cracking coil is combined in its operation with the pressure still, the reflux from the reflux tower of the pressure still, 10 or the reflux or heavier ends of the pressure distillate, may advantageously be utilized as charging stock for the auxiliary cracking coil, so that this reflux will be returned through the auxiliary cracking coil to the main body of oil in the pressure still. This reflux oil returned to the still itself may advantageously be admixed with fresh feed which may be utilized for assisting the refluxing action in the reflux tower and then supplied, freed from its lighter constituents and admixed with the reflux, to the auxiliary cracking coil, and subjected to a partial cracking operation therein before it is introduced into the pressure still itself.

By utilizing in the auxiliary cracking coil a 25 fresh charging stock or a mixed reflux and feed, which is free from carbon and tar constituents, the danger of objectionable carbon deposit on the walls of the auxiliary cracking coil is avoided or minimized, even though this cracking coil is 30 subjected to the intense furnace heat; while the furnace gases are sufficiently cooled by their contact with the auxiliary cracking coil so that intense heating of the walls or tubes of the pressure still itself is avoided, and a milder heating 35 of these walls or tubes obtained such that the danger of objectionable carbon deposit is reduced and the cracking operation can be carried to a further extent than would otherwise be feasible.

In the application of the invention in connection with a pressure still of the shell type, the auxiliary coil may be arranged in the heating flue or in the path of the hottest gases at an intermediate point between the firebox and the still proper, so that the furnace gases which come in contact 45 with the heating surfaces of the still will have been cooled considerably below their initial temperature, while the intense heat of the high temperature products of combustion from the firebox will be absorbed by the oil in the auxiliary 50 cracking coil. Where such a shell still is provided with a reflux tower, or where the distillate therefrom is subjected to refluxing and separation of the heavier constituents therefrom at a lower pressure than that of the still itself, the reflux, 55

either with or without additional feed, can be used as the charging stock of the auxiliary cracking coil and the cracked oil from such coil may then be introduced into the still proper.

5 Where the auxiliary cracking coil is combined with a tubular cracking still, the coil is similarly arranged between the firebox and the heating chamber or chambers containing the tubes through which the oil is circulated and in which 10 it is heated. This arrangement is of particular value in connection with such tubular cracking stills for the reason that it protects the tubes from the intense furnace heat and enables a milder heating of the tubes to be obtained. With such 15 a tubular still, the auxiliary cracking coil may likewise be combined to receive the reflux from the still itself or the heavier part of the distillate therefrom and may similarly discharge the partially cracked oil back into the main body of oil 20 undergoing cracking in the tubular still.

The invention is of special value and application in conjunction with pressure stills provided with reflux towers into which the fresh feed is introduced and from which the reflux and 25 mixed feed can be circulated through the auxiliary cracking coil before their introduction into the still proper. The reflux towers may be operated at the same pressure maintained in the pressure still and the refluxed oil, or refluxed 30 oil with admixed feed, circulated through the auxiliary cracking coil, either by gravity or convection circulation or by means of a pump; or the vapors from the pressure still may be reduced to a lower pressure and subjected to a re- 35 fluxing operation and the heavier refluxed distillate with or without admixed feed, pumped - through the auxiliary cracking coil and thence back to the main body of oil in the pressure still.

Where the reflux tower is operated at still 40 pressure, the tower and auxiliary coil may be so arranged relative to each other, and the coil may be so constructed that flow of the oil through the coil and into the still will be obtained by gravity and convection; although this circulation 45 may be effected or increased by means of a circulating pump or other means for increasing the circulation.

The invention will be further described in connection with the accompanying drawing illustrating an embodiment of the apparatus of the invention adapted for the practice of the process of the invention, but it will be understood that the invention is illustrated thereby but not limited thereto.

55 In the accompanying drawing,

Fig. 1 shows a tubular pressure still embodying the invention, the showing being largely conventional and diagrammatic, and partly in section and partly in elevation;

60 Fig. 2 is a sectional view of one end of the auxiliary cracking coil taken on the line 2-2 of Fig. 3;

Fig. 3 is a top view of the auxiliary cracking coil taken on the line 3-3 of Fig. 2.

65 While the invention is applicable in connection with cracking stills of different types; yet it is of particular advantage in connection with a tubular cracking still of the character illustrated. This cracking still is of the general construction 70 illustrated in U. S. Letters Patent No. 1,285,200, granted to the Sinclair Refining Company, November 19, 1918 on the application of Edward W. Isom.

The pressure still illustrated in Fig. 1 is made 75 up of the bulk supply tank 1 located away from

the heating furnace, the vertical heating tubes 2 arranged in the heating flue of the furnace, and circulating pipes 3, 4 and 5 connecting the lower and upper ends of the vertical tubes, respectively, with the bulk supply tank and a circulating pump 5 6 for circulating the oil from the bulk supply tank through the vertical tubes and back to the bulk supply tank. Arranged above the bulk supply tank is the reflux tower 7 having a series of baffles therein and connected with the vapor 10 dome of the bulk supply tank through the vapor line 8. An overflow reflux line 9 leads back from the reflux tower to the bulk supply tank, and prevents the liquid from rising to a level which will choke up the vapor line 8. The vapors from 15 the top of the reflux tower escape through the vapor line 10 to the condenser 12 where the vapors are condensed and received in the receiver 13 from which the uncondensed vapors and gas are drawn off through the pipe 14 and the liquid 20 condensate through the pipe 15. The pressure may be regulated and reduced by means of a regulating valve 11 between the reflux tower and condenser or by the valve 14 located beyond the receiver. 25

The furnace construction for heating the tubes of the still comprises a firebox 16 suitably heated as by gas or oil burners 17, a vertical flue 18 leading upwardly from the firebox to the upper end of the heating flue containing the vertical 30 tubes, a heating flue having baffles 20 and 21 therein for causing the gases to pass over the vertical tubes in three successive passes and an outlet flue 22 leading to the stack.

Located above the bridge wall 19 and between 35 the vertical flue 18 and the flue containing the vertical tubes 2 is the auxiliary cracking coil 23 having an inlet connecting pipe 24 and outlet pipe 25 leading to the manifold at the upper ends of the vertical tubes. A pipe 26 having a valve 40 27 therein connects the inlet of the coil to the discharge side of the circulating pump 6. This pipe may be used in starting the still in operation, as well as in draining the auxiliary coil and connecting piping when the still is pumped out. 45

An auxiliary tank or reservoir 28 is arranged to receive the reflux and admixed feed from the reflux tower 7 through connections 29. This tank or reservoir has a vent pipe 30 leading back 50 to the reflux tower. The tank or reservoir 28 is also connected through the pipes 31 and 32 to the feed line 24 of the auxiliary coil. A pump 33 is arranged to pump the oil through the auxiliary coil, while the connecting pipe 34 permits circulation by gravity and by convection when the pump 33 is not used. A branch pipe 36 leads from connection 32 to the bottom of the bulk supply tank. The pipes 31 and 36 have control valves therein by which one or the other or both of these pipes can be shut off when desired. A feed line 35 enters the inlet pipe 24 of the auxiliary coil and permits the direct introduction of fresh feed as it is desired. A tar draw-off connection for use during the operation 60 of the still is shown at 37 and a tar draw-off for discharging the still is shown at 38.

The auxiliary reservoir or tank 28 is located within the bulk supply tank 1, although it is not in open communication therewith except through 70 the pipe connections. It will be evident that valves such as those in the pipes 31 and 36 should have operating handles which extend out through suitable stuffing boxes in the walls of the bulk supply tank. Test cocks (not shown) may be pro- 75

vided for ascertaining the level of the oil in this auxiliary tank or reservoir.

A feed line 39 is provided for feeding fresh oil to the top of the reflux tower 7. An additional feed line 40 is provided for feeding oil to the bearings of the pump 6. Additional feed can also be introduced through the auxiliary coil through the feed line 35 as above noted.

The auxiliary coil 23 is made up of a series of 10 pipes connected at their ends as indicated in Figs. 2 and 3 and arranged so that the oil flows therethrough in a single pass in a generally upward direction, the flow being thus assisted by convection.

15 When the still is initially charged, oil may be circulated from the main charge of oil through the auxiliary cracking coil, for example, by closing the valve in the pipe 31 and opening the valve in the pipe 36 when the circulating pump 20 33 will draw oil from the bulk supply tank 1 and circulate it through the auxiliary coil; or the valve 27 may be opened and oil from the discharge side of the pump 6 may be circulated through the auxiliary coil; or fresh feed may be 25 introduced through the feed line 35.

After the pressure still has been raised to cracking conditions of temperature and pressure, the cracked vapors from the still will rise in the reflux tower 7 and will come in contact 30 with the fresh feed introduced through the line 39 to the top of the tower. By providing a sufficient number of baffles practically all of the feed for the still can be introduced in this way and a pressure distillate approximating a gasoline 35 distillate directly obtained with return of the heavier constituents in the liquid state to the bottom of the reflux tower. This reflux and admixed feed collects in the reservoir or tank 28 which, in a still of the type illustrated, may 40 have a capacity for example of about one thousand gallons. From this reservoir the oil is circulated either by gravity or convection or by pump, through the auxiliary cracking coil 23 where it is subjected to the intense heat of the 45 hottest gases from the furnace. The cracked oil is discharged into the top circulating line of the still and is returned to the bulk supply tank. The unvaporized portion of the oil so returned forms a part of the still charge and is circulated 50 therewith through the vertical tubes. It will be evident that the rate of circulation of the oil should be regulated so that a constant supply is provided and so as to maintain a level of oil in the reservoir 28. By introducing all or practically all of the fresh feed into the top of the 55 reflux tower and bringing it into intimate contact with the vapors therein, a constant supply of reflux and admixed feed is provided. Should the reservoir 28 become full the additional reflux and feed will collect in the bottom of the reflux tower and will overflow through the pipe 9 to the bulk supply tank 1.

In a still of the construction illustrated, when 60 the auxiliary coil is not provided, the greater part of the heat is absorbed in the front rows of tubes in the upper pass of the heating chamber where the hot furnace gases first come in contact with the tubes. In the commercial operation of such stills, around six million to eight 65 million B. t. u. are absorbed per hour by the oil. By interposing the auxiliary coil where it will be subjected to the hottest gases from the furnace, the temperature of these gases will be reduced, for example, from around 2400° F. to around 70 75 1600° F. by their passage through the auxiliary

coil and a large proportion of the heat will be absorbed in this way at the maximum temperature of the heating gases. Where, however, the oil fed through this auxiliary coil is admixed feed and reflux which is free from tar, the coil can 5 be subjected to such high temperatures and a large amount of heat can be absorbed thereby without objectionable carbon deposit on the walls of the tubes of the coil.

After the high temperature furnace gases have 10 been reduced in temperature by passage through the auxiliary coil, they then pass over the vertical tubes of the pressure still at a lower temperature and serve to heat these tubes without danger of objectionable overheating. A milder 15 heating and cracking action is thus obtained so that the still charge can be cracked to a further extent without danger of objectionable carbon deposit on the tubes and with the obtaining of heavier residuum from the cracking operation. 20

In a commercial still of the character illustrated, the auxiliary cracking coil may be made up of four inch pipe and the oil may be circulated therethrough at a regulated rate so that objectionable overcracking will be avoided while 25 effective cracking will nevertheless be obtained, and the resulting cracked oil will then be introduced into the pressure still to admix with the oil and vapors therein.

The operation of the pressure still in this way, 30 with circulation of the feed and reflux through the auxiliary coil, and with circulation of the main charge of the still through tubes heated to lower temperatures, gives an increased furnace efficiency with longer running time before it is 35 necessary to shut down for cleaning, and with increased capacity of operation of the pressure still, while also permitting a reduction of pressure tar while under pressure to a lower gravity without detriment to the operation. 40

The higher temperature to which the auxiliary cracking coil is subjected also permits the cracking therein of kerosene fractions and lighter oils which are more difficult to crack in ordinary pressure stills. Such kerosene fractions may be 45 those produced by the pressure still itself or supplied from another source.

The addition of an auxiliary cracking coil in conjunction with the operation of the pressure still also permits the introduction of an increased 50 amount of feed through the top of the reflux tower and a fractionation of the vapors from the still to much nearer a finished gasoline than is commonly obtained, and this without any difficulty in regular operation. 55

The pressure still may be further protected from the intense furnace heat by recirculating a part of the heating gases which have passed over the heating surfaces of the still and admixing this recirculated cooler gas with the fresh 60 heating gases from the furnace before they are passed over the heating surfaces of the still proper, so that the heating gases used for heating the main charge of oil in the still itself are tempered by the combined effect of the recirculated gases and the action of the auxiliary cracking coil in absorbing the initial intense heat of the heating gases. The recirculation of waste heating gases in this way increases the velocity 65 of flow of the heating gases improving heat transfer and since the waste heating gases are returned at substantially the temperature at which they would otherwise be discharged, both the efficiency and capacity of the pressure still may be further increased. The waste heating gases may 70 75

be recirculated by means of a blower, as illustrated, or by other suitable means.

It will thus be seen that by this improved construction and method of operation of pressure stills, the intense furnace heat of the heating furnace is utilized in an auxiliary cracking operation where such intense heat is advantageous, and that the cracking operation of the main pressure still is carried out with the furnace gases which have been cooled by their utilization in the preliminary cracking operation.

It will further be seen that the preliminary cracking operation which utilizes the intense heat of the highest temperatures of the furnace may advantageously be combined with the operation of the pressure still utilizing the furnace gases subsequently at a lower temperature such that a milder cracking action is obtained; and that, where these operations are combined, the feed for the auxiliary cracking coil may advantageously be supplied in the form of reflux, or of reflux and admixed feed from the reflux tower of the pressure still.

The temperature and pressure employed in the carrying out of the process and in the operation of the apparatus can be varied with different characters of charging stock. Where ordinary gas oil is employed in the main pressure still pressures of around 90-125 lbs. may be employed; while with lighter oils, higher pressures may be used, for example of around 300-325 lbs. The pressure maintained in the auxiliary cracking coil may be the same as that in the pressure still or only enough higher to cause the desired circulation; or the auxiliary cracking coil may be maintained at a considerably higher pressure and the pressure reduced in case the cracked oil is to be discharged into the pressure still at a lower pressure.

I claim:

1. A hydrocarbon oil cracking process which comprises passing the oil through a heating zone and heating the oil therein to a cracking temperature, separating evolved vapors from unvaporized oil in a vapor separating zone and sub-

jecting said vapors to dephlegmation thereby forming reflux condensate, collecting said reflux condensate in a body out of contact with vapors evolved in said vapor separating zone, withdrawing a portion of the reflux condensate from said body, separately heating said portion to a temperature higher than that to which the oil is heated in said first mentioned heating zone and thereby vaporizing a portion of said condensate, passing vapors evolved by said separate heating in indirect heat exchange relation with said body of reflux condensate, combining with the vapors being dephlegmated vapors evolved by said separate heating of the reflux condensate and vapors evolved from said collected body of reflux, and condensing the dephlegmated vapors.

2. An apparatus for cracking hydrocarbon oils comprising a furnace structure having a fire box and a heating chamber, a tubular heater arranged in the heating chamber of said furnace, a vapor separating chamber, means for passing oil to be cracked through said heater and thence into said vapor separating chamber, a dephlegmator and a connection for conveying vapors from said vapor separating chamber to said dephlegmator, a reflux collecting receptacle arranged within said vapor separating chamber above the normal liquid level therein, a reflux return connection leading from the lower end of said dephlegmator to said reflux collecting receptacle, a vent leading from the upper portion of said reflux collecting receptacle to a point in said dephlegmator above the juncture of said reflux return connection, a second tubular heater arranged in said furnace between the fire box and the first mentioned tubular heater, means for withdrawing liquid from the lower portion of said reflux collecting chamber and supplying it to one end of said second tubular heater, a connection leading from the other end of said second tubular heater to said vapor separating chamber, and means for condensing vapors discharged from said dephlegmator.

EUGENE C. HERTEL.
